UNITED STATES PATENT OFFICE.

JAMES FOSTER KING, OF WASHINGTON, DISTRICT OF COLUMBIA.

WIRELESS TELEGRAPHY.

No. 813,975.

Specification of Letters Patent.

Patented Feb. 27, 1906.

Application filed January 8, 1903. Serial No. 138,276.

To all whom it may concern:

Be it known that I, JAMES FOSTER KING, a citizen of the United States, residing at Washington, in the District of Columbia, have invented certain new and useful Improvements in Wireless Telegraphy; and I do hereby declare the following to be a full, clear, and exact description of the invention, such as will enable others skilled in the art to which it applies to make and use the same.

More especially, my invention relates to those wireless or space telegraphs in which the receiving apparatus depends for its operation upon the conjoint action of a generator current or currents, by which a receiver is constantly or normally excited, and one or more received oscillations. This idea is broadly covered by United States Patent No. 729,497, granted to me May 26, 1903.

The present invention is specifically different from that shown in the patent above referred to, principally in the following respect: The method employed in the patented invention consists in augmenting the current in a normally closed receiver-circuit by impressing thereon an extra electromotive force induced by the reception of one or more oscillations. The present invention contemplates normally impressing local generator-currents on two branch circuits, causing the currents in said circuits to set up opposing magnetic fields, one of which is normally stronger than the other, subjecting a body normally to the opposing actions of said fields, and causing received oscillations to act to vary the normal relation between said fields.

My invention will be more clearly understood by referring to the accompanying diagram, which shows one arrangement of circuits and apparatus by which the invention may be carried out.

Referring to the accompanying diagram, A represents a vertical wire in circuit with which is connected a primary b of a transformer B.

C indicates a generator of alternating or other periodical currents connected to a main generator-circuit 1, 2. This main generator-circuit divides into two branch circuits 3 and 4.

D represents what I shall designate a "differential relay" having two coils d , d' , adapted to create opposing magnetic fields which are made to act upon a tongue d^2 . The tongue of this relay is normally pulled by spring d^3 against a spring-plunger d^4 into close proxim-

ity to a forward contact-stop d^5 . The coil d' is connected in the branch circuit 4 in series with secondaries b' of the transformer B, while coil d is connected in the branch circuit 3. 60

E indicates a telegraphic sounder or other receiving device connected in the relay-circuit 5 together with the battery F.

The currents in the main circuit 1, 2, as well as the branch circuits 3 and 4, may be brought into proper phase with the several electromotive forces acting in the respective circuits, and thereby produce maximum resulting magnetic effects at the poles, by a proper adjustment of condensers G , G' and G^2 . The condensers G , and G^2 may serve also to prevent foreign oscillations from affecting the relay D.

Although I have shown the coils d and d' wound upon iron cores, there are conditions under which iron may be omitted.

The facing poles set up by the current in the coils d and d' oppose each other, that is, the two fields exert force in opposite directions on the tongue d^2 . Owing to the impedance in the circuit 4 introduced by the secondaries b' , or to a larger number of turns of coil d' than of coil d , the current from the generator will pass unequally through the branch circuits 3, 4, the branch 4 receiving less current owing to its greater impedance. The coil d will, therefore, exercise a preponderating effect on the tongue d^2 over that of the coil d' . This is the normal condition under which the tongue d^2 is held away from the forward contact d^5 . When a received oscillation impinges on the vertical wire, this will set up an induced electromotive force in the secondaries of the transformer B, which, added to the normal electromotive force of the branch circuit 4, will cause the magnet-coil d' to increase its pull to such an extent as to reduce the preponderating pull of the coil d sufficiently to allow the spring d^3 to pull the tongue d^2 against the contact d^5 , thus sending current through the local receiving device E, as will be readily understood.

Having thus described my invention, what I claim is—

1. The method of receiving wireless-telegraph messages which consists in normally impressing local generator-currents on two branch circuits, causing the currents in said circuits to set up opposing magnetic fields one of which is normally stronger than the other, and causing received oscillations to act to vary the normal relation between said fields. 105 110

2. The method of receiving wireless-telegraph messages which consists in normally impressing local generator-currents on two branch circuits, causing the currents in said circuits to set up opposing magnetic fields one of which is normally stronger than the other, subjecting a body normally to the opposing actions of said fields, and causing re-

ceived oscillations to act to vary the normal relation between said fields.

In testimony whereof I affix my signature in presence of two witnesses.

JAMES FOSTER KING.
